Primary Examiner — Sheryl Lane*Assistant Examiner* — Ieisha Price*(74) Attorney, Agent, or Firm* — Medley, Behrens & Lewis, LLC; Lorri W. Cooper**CLAIM**

The ornamental design for a bookmark, as shown and described.

DESCRIPTION

FIG. 1 is a perspective view of a bookmark showing my new design.

FIG. 2 is a front view of the bookmark shown in FIG. 1; FIG. 3 is a back view of the bookmark shown in FIG. 1; FIG. 4 is a left side view of the bookmark shown in FIG. 1; FIG. 5 is a right side view of the bookmark shown in FIG. 1; FIG. 6 is a bottom view of the bookmark shown in FIG. 1; and, FIG. 7 is a top view of the bookmark shown in FIG. 1.

The broken line shown in FIG. 1 illustrates the environment of the claimed design and forms no part thereof.

The dash-dot-dash lines shown in FIGS. 1-5 define the bounds of the claimed design and form no part thereof.
